[57] CLAIM

The ornamental design for a kitchen knife handle, as shown and described.

DESCRIPTION

FIG. 1 is a side elevational view of a kitchen knife handle showing my new design, the side opposite is a mirror image thereof;

FIG. 2 is a top plan view thereof;

FIG. 3 is an end elevational view seen in the direction of arrow "A" in FIG. 1;

FIG. 4 is an end elevational view seen in the direction of arrow "B" in FIG. 1; and

FIG. 5 is a fragmentary cross-sectional view thereof taken on line 5—5 of FIG. 1.

The broken line showing of the blade in FIGS. 1 and 2 is for illustrative purposes only and forms no part of the claimed design.

FIG. 1.

FIG. 2.

A

FIG. 5.

FIG. 4.

FIG. 3.
